Joseph V. Hansen and Frank P. Stewart,
Salt Lake City, Utah

Application September 19, 1952, Serial No. 21,521

Term of patent 7 years

(Cl. D33—8)

To all whom it may concern:

Be it known that we, Joseph V. Hansen and Frank P. Stewart, citizens of the United States, residing at Salt Lake City, in the county of Salt Lake and State of Utah, have invented a new, original, and ornamental Design for a Tie Rack, of which the following is a specification, reference being had to the accompanying drawing, forming part thereof.

Figure 1 is a perspective view of a tie rack, showing our new design, and

Figure 2 is a front elevational view thereof.

The dominant features of our design reside in the portions shown by full lines.

We claim:

The ornamental design for a tie rack, as shown and described.

JOSEPH V. HANSEN.
FRANK P. STEWART.
